UNITED STATES PATENT OFFICE.

LYMAN C. JOSEPHS, JR., OF ALLENTOWN, PENNSYLVANIA, ASSIGNOR TO INTERNATIONAL MOTOR COMPANY, OF NEW YORK, N. Y., A CORPORATION OF DELAWARE.

CONTROL DEVICE FOR SANDERS.

Application filed October 25, 1924. Serial No. 745,740.

This invention relates to automatic devices for controlling selectively one of two sanders depending upon the direction of travel of the vehicle on which the sanders are mounted. More particularly, the invention is concerned with such devices when combined with sanders adapted for electro-pneumatic operation. Heretofore, it has been the general practice to mount separate sanders at opposite sides of a vehicle wheel and where these sanders have been of electro-responsive type appropriate control circuits have been placed within reach of the operator whereby one circuit might be cut out and the other cut in manually depending upon the direction of travel of the vehicle. In accordance with the present invention it is proposed to employ electro-responsive controls for the sanders and associate with their respective circuits a switch element which itself is actuated automatically upon actuation of the mechanism for reversing the direction of travel of the vehicle. The circuit control thus effected is such as to cut in one sander and cut out the other automatically.

One preferred embodiment of the improvements has been shown in the accompanying drawings in connection with the application of sanders to a rail car in which change speed devices of conventional type are employed, the control switch for the sander circuits being movable in this embodiment with the shifter rod for the reverse gear.

In the drawings:

Figure 1 is a view in side elevation showing a sand reservoir with appropriate pipe connections for an air blast, an electro-responsive device for controlling the blast, suitable control circuits for two such electro-responsive devices and, conventionally, a reverse gear shifter rod with which a control switch is carried.

Figure 2 is a view in end elevation showing pipe connections from the sand reservoir leading to the opposite sides of a wheel of a vehicle.

Figure 3 shows conventionally circuits for two electro-magnets for controlling the air blast which, in accordance with the improvements, are controlled selectively by a switch.

It will be understood as the description proceeds that the invention is not concerned with any of the details of the sanding mech-

anism per se nor, indeed, with the devices by which the discharge of sand is effected. For the purposes of this application, however, it may be assumed that a sand reservoir *a* is mounted on a rail car and has leading therefrom two downwardly extending sand pipes, one of which *a'* may discharge onto the track at one side of a vehicle wheel and the other of which *a''* may discharge on the other side of the same wheel in accordance with accepted practice. The discharge of sand through either one of these pipes may be effected by an air blast admitted through a suitable nozzle one of which is indicated for the pipe *a'* at *b*. A pipe *c* for another similar nozzle for the sand pipe *a''* is indicated in Figure 1, the nozzles being, of course, side by side. An electro-magnet indicated at *d* may actuate a suitable pneumatic valve by which a blast of air through one of the nozzles, say *b* from an air line *e* is admitted. A similar magnet *f* and valve are disposed right alongside of the magnet *d* to control an air blast through the pipe *c* for the other sander pipe *a''*. Both of these magnets are, of course, grounded. The circuit wire for the magnet *d* is shown at *d'* and the circuit wire for the other magnet is shown at *f*. These wires are connected, respectively, to switch contacts *d'', f'*. Other switch contacts are indicated at *d''', f''*, and connected to a feed line *g*. A switch *h* is illustrated as movable to close either one of the circuits *d', f*, by bridging the respective pairs of contacts *d'', d'''*, or *f'', f'''*. In its broader phases the invention contemplates that such a switch may be movable with any part of the reversing mechanism of a rail car. The particular embodiment shows the switch carried with the shifter rod *i* which may be assumed to engage through a fork *j* the reverse gear in a conventional change speed transmission. Naturally, a shifter rod *i* must be moved axially whenever the direction of travel of the car is to be changed. Actuation of the shifter rod *i*, then, results in the closing of one or the other of the circuits, the appropriate circuit being selected for sanding when required on the proper side of the vehicle wheel. As indicated in Figure 3, of course, the actual sanding may always be under the control of the operator through a single manually controlled switch *k* in the feed wire *g* but which of the two

magnets d , f^3 , is energized depends, of course, upon which of the circuits f , d' , is closed by the switch element h , in the manner described.

5 As indicated hereinbefore, no limitation as to the structural details of the sanding device and their operating means is intended since the principle of the invention is concerned entirely with the selection of appropriate sanding mechanism depending upon 10 the direction of travel of the vehicle. The appended claims will define more particularly the breadth of the improvements.

What I claim is:

15 1. In a vehicle, in combination with a plurality of sanders, electro-responsive devices to control the operation of the respective sanders and selective devices independent of the power control means and associated with the directional control mechanism for the vehicle to control the circuits of 20 said electro-responsive devices.

2. In a vehicle, in combination with a plurality of sanders, electro-responsive devices to control the operation of the respec- 25

tive sanders, and a switch movable upon movement of the reversing mechanism and independent of the power control means for the vehicle to control the circuits of said electro-responsive devices. 20

3. In a vehicle, in combination with a plurality of sanders, electro-responsive devices for controlling the operation of the respective sanders, reverse speed mechanism for the vehicle and a switch movable with said reverse speed mechanism and independent of the power control means to control the circuits of said electro-responsive devices. 35

4. In a vehicle, in combination with a plurality of sanders, electro-pneumatic devices for operating the respective sanders, a transmission including reverse speed means, and a switch element carried with the reverse speed means to control the circuits of the respective electro-pneumatic devices selectively upon movement of the reverse speed mechanism. 40 45

This specification signed this 23 day of October A. D. 1924.
